UNITED STATES PATENT OFFICE

LEWIS E. HILER, OF RYE, NEW YORK

DESIGN FOR A TEXTILE FABRIC

Application filed September 22, 1931. Serial No. 41,187. Term of patent 3½ years.

To all whom it may concern:

Be it known that I, LEWIS E. HILER, a citizen of the United States of America, and resident of Rye, county of Westchester, and State of New York, have invented a new, original, and ornamental Design for a Textile Fabric, of which the following is a specification, reference being had to the accompanying drawing, forming a part thereof.

The figure is a plan view of a textile fabric, illustrating my new and ornamental design. A unit of the design is contained within the dot and dash lines A, B, C, D, which unit is repeated in the relation wherein the angle B coincides with B' and A with A'.

I claim:

The ornamental design for a textile fabric as shown and described.

LEWIS E. HILER.
